UNITED STATES PATENT OFFICE.

AXEL FREDRIK ABRAHAMSON ROXENDORFF, OF STOCKHOLM, SWEDEN.

DRIVING MECHANISM FOR BICYCLES.

SPECIFICATION forming part of Letters Patent No. 627,881, dated June 27, 1899.

Application filed December 24, 1897. Renewed April 15, 1899. Serial No. 713,175. (No model.)

To all whom it may concern:

Be it known that I, AXEL FREDRIK ABRAHAMSON ROXENDORFF, mechanical engineer, a subject of the King of Sweden and Norway, and a resident of Stockholm, Sweden, have invented certain new and useful Improvements in Driving Mechanism for Varying the Exertion of Power in Bicycles and other Vehicles, (patented by me in the following countries: Sweden, No. 8,392, September 11, 1896; France, No. 263,175, January 18, 1897; Great Britain, No. 6,338, March 10, 1897; Italy, Vol. XXXII, No. 44,064, and Vol. LXXXVI, No. 229, March 9, 1897; Belgium, No. 126,861, 15 March 9, 1897, and Austria, No. 47/2,827, July 28, 1897,) of which the following is a specification, reference being had therein to the accompanying drawing.

This invention has for its purpose to secure to me the exclusive right to certain constructions of bicycles and other vehicles in which the driving mechanism consists of oscillating treadles to which are secured chains or other driving means having one end fastened to a 20 friction or ratchet coupling acting on the hub of the driving-wheel, one such coupling being located on each side, while the other end of the chain D is fastened to the treadle, said driving means passing over a block or pulley 25 E, movably attached to the frame. The center of oscillation of the treadle coincides with the center of the driving-wheel, or at least lies near it.

The motion of the oscillating treadles is transferred to the hub of the driving-wheel, on which act two friction or ratchet couplings F, one on each side, on which the driving means are wound and unwound. By depressing the treadle on one side motion is 30 transmitted to the coupling F, which rotates the driving-wheel forward, while the driving means belonging to the other treadle is simultaneously wound onto its corresponding coupling by a special mechanism, raising 35 said treadle, which at that time is inactive. The leverage is varied by moving the block or disk E longitudinally with reference to the frame or between the extremities A' and A², said movement being effected by means 40 of the rods k, one on each side of the frame. These rods are united to a ring H, sliding on some easily-accessible tube of the frame, and which ring by means of a small eccentric or other contrivance can be stopped anywhere 45

on said tube for producing the leverage desired. By this method the angle α between the treadle and the driving means is increased or decreased, and consequently the pull on the driving means (denoted by the force a or a' in the drawing) will vary in amount according to the size of the angle α . A uniform force b is, however, in this case exerted in the vertical direction by the foot of the rider. (See the parallelogram of forces in the drawing.) If the block E be shifted between A' and A², it is evident that the tension in the chain will vary between a and a'. In the case when the block E is placed in the position A' the force a acting on the chain will be smaller, but the velocity greater than if these parts be placed at A², in which case the force a' will be greater, but the velocity smaller. The block E slides on an elliptic arc B, having a focus at the center of the driving-wheel, while its other focus coincides with the point of attachment of the chain on the treadle when the latter is in its middle position. The treadle consequently has the same middle position no matter where the block E is located between A' and A². 55 60 65 70 75 80

In the drawing the center of oscillation of the treadle is located at the center of the driving-wheel. It is evident, however, that the former can be located at some distance from the latter. 85

Having now described my invention, what I claim as new, and desire to secure by Letters Patent, is—

In a bicycle or similar vehicle, the combination with the frame, the driving-wheel, the hub and the axle, the coupling adapted to engage with said hub, and the elliptic bar secured to the frame, of the fulcrum bar or rod working on said elliptic bar, the disk or block journaled thereto and means for adjusting the same, the treadle and the treadle-bar and the chain connected with said coupling and directly connected to the treadle, and passing over said disk or block, substantially as described. 90 95 100

In witness whereof I have hereunto signed my name in the presence of two subscribing witnesses.

AXEL FREDRIK ABRAHAMSON ROXENDORFF.
